UNITED STATES PATENT OFFICE

167,472

PLATE OR SIMILAR ARTICLE

Toni Olga Muench, East Liverpool, Ohio, assignor
to Fisher Bruce & Company, Philadelphia, Pa., a corporation of Pennsylvania

Application April 2, 1952, Serial No. 19,159

Term of patent 7 years

(Cl. D44—15)

To all whom it may concern:

Be it known that I, Toni Olga Muench, a citizen of the United States, residing in East Liverpool, Columbiana County, and State of Ohio, have invented a new, original, and ornamental Design for Plate or Similar Article, of which the following is a specification, reference being had to the accompanying drawing, forming a part hereof.

The single figure is a top plan view of a plate or similar article, showing my new design, the dominant features of which reside in a turkey in flight over a patch of vegetation with a field and woods in the background, and a border which is repeated around the periphery between the broken lines, as shown.

I claim:

The ornamental design for plate or similar article, as shown and described.

TONI OLGA MUENCH.
